TOY MANIFOLD EXHAUST FOR TOY WHEELED VEHICLES

Harry Golden, New York, N.Y., assignor to Ideas for
Auto & Bike Specialties, Inc., New York, N.Y., a cor-
poration of New York

Filed Nov. 29, 1963, Ser. No. 77,606

Term of patent 7 years

(Cl. D34—15)

FIG. 1

FIG. 2

FIG. 3

FIG. 4

FIG. 5

FIG. 6

FIGURE 1 is a side elevational view of a toy manifold exhaust for toy wheeled vehicles embodying my new design;

FIGURE 2 is a rear elevational view thereof;

FIGURE 3 is a top plan view of the same;

FIGURE 4 is a one end elevational view thereof;

FIGURE 5 is an opposite end elevational view of the same; and

FIGURE 6 is a vertical sectional view through the same, as seen on the line 6-6 of FIGURE 2, looking in the direction of the arrows.

The design is characterized by the representation for toy automobiles of a series of exhaust pipes supported in spaced relation on a solid integral back plate with

arcuately formed portions connected respectively with the inner end portions of said pipe representations and said pipe representations each terminating in a concaved end portion all as shown.

I claim:

The ornamental design for toy manifold exhaust for toy wheeled vehicles, as shown and described.
